INSULATING JACKET FOR POTS OR THE LIKE

Peter Schlumbohm, 41 Murray St., New York, N.Y.

Filed Aug. 30, 1961, Ser. No. 66,553

Term of patent 14 years

(Cl. D44—10)

FIG. 3

FIG. 1

FIG. 2

FIG. 4

FIG. 1 is a perspective view of an insulating jacket for pots or the like showing my new design;

FIG. 2 is a side elevational view;

FIG. 3 is a top plan view; and

FIG. 4 is a side elevational view with a pot shown in broken lines for illustrative purposes.

The insulating apparatus is preferably molded from plastic insulating material such as Dylite or Urethane foam or Fiberglas or the like, but it may also be built in double-walled fashion with insulating material or a vacuum between the two walls.

I claim:

The ornamental design of an insulating jacket for pots or the like, as shown and described.
